REMOTE CONTROL DOOR OPERATOR

Walter Galeazi, San Francisco, Calif.

Application April 5, 1940, Serial No. 327,957

4 Claims. (Cl. 268—34)

This invention relates to improvements in remote control door operators, and more particularly to a combined electrical control and hydraulic door opening mechanism.

Among the objects of the invention is to enable the driver of an automobile to open the garage doors without leaving the automobile.

Another object is to prevent the opening of the doors from without except by the means provided.

Another object is to prevent injury to the door mounting by the operation of the hydraulic ram.

Another object is to provide for the silent opening and closing of the doors.

A further object is to provide full automatic opening and closing of the doors.

Other objects and advantages will appear as the description progresses.

Broadly stated the invention consists of a remote control magnetic switch buried in the approach to the door. This switch controls a relay circuit having magnetic fluid valves therein for admitting and discharging fluid pressure to a hydraulic ram to supply the force for opening the doors, applied through flexible means for and synchronously releasing the door latches.

The opening of the doors opens the remote control circuit and closes a subcircuit and reverses the valve control to discharge the fluid pressure when the remote control circuit is subsequently closed by a manual switch.

The doors are closed and the various mechanisms restored to normal by gravity weights operating through flexible cables attached to their respective parts, or other form of door closers.

In this specification and the accompanying drawings the invention is disclosed in its preferred form. But it is to be understood that it is not limited to this form, because it may be embodied in modifications within the spirit of the invention as defined in the claims following the description.

In the one sheet of drawing:

Fig. 1 is a diagrammatic plan view of an installation in accordance with this invention, partially in horizontal section, with the wiring diagram superimposed on the structural diagram.

Fig. 2 is a reduced detail in elevation of the inside of the doors and latch equipment.

Fig. 3 is an enlarged detail in vertical section of a conventional magnetically controlled water valve adapted to the present purpose.

In detail the construction illustrated in the drawing comprises the front wall fragmentally illustrated at 1, 2, and the side walls 3, 4. The

doors 5, 6 are hinged at 7, 8 respectively to the door jambs 9, 10. The doors meet at the center, the door 6 having the stop 11 overlying the meeting edge, as usual.

The hydraulic mechanism has a supporting frame with the guide bars 12, 13 attached to the ceiling, not shown, or to the ceiling and front wall above the door opening if architectural conditions permit. The cylinder 14 is mounted between these guide bars by the interposed brackets 15, 16.

The front end of the cylinder is closed by the T fitting 18. The piston 19 is fixed on the end of the piston rod 20 which passes through the guide 21 in the opposite end of the cylinder. The cross-head 22 is fixed on the outer end of the piston rod and is guided by the flanged rollers 23, 24 riding on the guide bars 12, 13. The lineal extensions of these bars have been broken away in the interest of clarity in the drawing.

The cable 25 is fixed to the side of the cross-head 22, passes around the pulley 26 on the bracket 27, that is mounted on the frame of the guide bar 12; thence through the pulley 28, attached to the side wall 3; thence down over the pulley 29 and is attached to the end of the arm 30, pivoted to the door 5 at 31, see Fig. 2.

The top and bottom door latches 32 and 33 are released by the chains 34, 34¹ attached to the arm 30 on opposite sides of the pivot 31.

The other door cable 35 is attached to the opposite end of the cross-head 22; passes around the pulley 36 on the bracket 37, that is mounted on the frame of the guide bar 13; thence through the pulley 38 attached to the side wall 4; thence to the bracket 39, extending outwardly from the door 6.

The doors are synchronously unlatched and opened by the pull of the cables 25, 35. The doors are closed by the counter balancing weights 40, 41 on their respective cables 42, 43, passing around the pulleys 44, 45, mounted on the front wall 1—2 and around their respective pulleys 46, 47 mounted on the ceiling overhead, and have their ends fixed to their respective brackets 39, 48. These counterweights 40, 41 rise as their respective doors swing open. The spring latches 31, 32, automatically lock the door 5 when it closes.

The fluid pressure medium such as city water service enters through the pipe 49, through the magnetically operated inlet valve 50, see Fig. 3, into and out of the cylinder 14 through the T fitting 18, and is discharged through the outlet valve 51, and the overflow pipe 52.

The remote control switch 55 at A, is preferably of the mercury contact type. It consists of the sealed casing 53 having the mercury 54. The armature 55 is pivoted at 56 in the casing and has the contactor 55' adapted to dip into the mercury to close the circuit represented by the wires 57, 58, respectively terminating in the mercury 54 and the armature 55.

The casing 53 has the external pole piece of soft iron 59 arranged in proximity to the armature 55 and to the electromagnet 60 mounted on the automobile not shown. This magnet generates a magnetic field to swing the armature 55 against the counter balance 56¹, when the switch 62 in the automobile is closed to pass the current from the battery 63 through the magnet 60. This causes the contact 55¹ to dip into the mercury 54 closing the circuit 57, 58 and admitting the main line service 64, 65 to flow in through the transformer B.

The relay magnet 66 at C is energized through the wire 58 and the six volt take off from the transformer at B through the wire 67. Energizing the relay at C, attracts the armature 68, which closes the twenty four volt sub-circuit over the wire 69, through the normally closed switch 70 at D; thence over the wire 71 back to the twenty four volt take off from the transformer B.

Energizing the relay at C, close the contact 39 through the armature 68; permitting current to flow over the wire 72, across the switch 73, the wire 74, through the magnet 75, over the wire 76, over the wire 57 back to the transformer at B, completing the circuit.

A third circuit is closed by the relay switch 75 at E, causing current to flow across the contacts 77, 78. Contacts 79, 80 are also closed because the switch at E is double pole. Service current—110 volts—can now flow from wire 65 over wire 83, contacts 79, 80, wire 85 at H, switch 85, wire 86 to the magnetic valve 50 and return over wire 87 to the main service wire 64 to open the inlet valve 50.

The opening of the inlet valve 50 admits fluid pressure into the cylinder 14 behind the piston to unlatch the doors at 31, 32 and swing them open through the operation of their respective cables 25, 35 as previously described.

The switch 70 at D is normally closed by the cross head 22 when the doors 5, 6 are closed and the hydraulic mechanism is collapsed. As the cross head advances the switch 70 at D opens, but this is of no consequence because of the new circuit over the wire 81, previously described.

When the cross-head 22 reaches the end of its outward stroke, the lug 88 on the cross-head opens the switches 73, 85 at G and H respectively. This is a double pole switch similar to D, but is shown divided for clarity. The opening of the limit switch 85, kills the magnetic inlet valve 50, permitting it to close and shut off the fluid pressure from the pipe 49.

While the doors are in the open positions current continues to flow through the relay 75 at E. But the opening of the other limit switch 73 at G, killed the relay C opening the switch at 68.

When it is desired to close the doors from within the garage the manual switch 90 connected in multiple across the wires 57, 58 is closed. This energizes the relay 66, which breaks the circuit through the relay 75 over the wire 91, permitting the switch 79 at E to drop and close the discharge valve contact 92 permitting current to flow from the service wire 63 over the wire 93 75

to the contact 94, across the switch 79, and over the wire 95 to energize the discharge valve 51; thence over the wire 96 and over the wire 81 to the main wire 64.

5 The opening of the discharge valve 51 permits the fluid pressure to flow from the cylinder 14, and the counterweights 40 and 41 to close their respective doors 5, 6 in unison and restores the apparatus to normal with all control circuits open for a repeat operation of the automatic door opening, previously described.

While the manual switch 90 is provided for opening and closing the doors, it is obvious that a magnetic mercury switch such as A provided beneath the automobile in the garage could be provided to be operated by the magnetic field at 60, for the same purpose.

Thus equipped the driver could take his seat in the automobile and close the switch 62 and 20 back out of the garage after the doors opened. By pausing over the remote switch at A the door could be automatically closed by closing the switch 62. The doors can be either opened or closed from the driver's seat without leaving the 25 automobile whether it be without or within the garage.

To facilitate the return of the hydraulic ram to normal or closed position, the cable 97 is attached to the cross-head 22 and passed around the necessary pulleys to suspend the counterweight 98.

In this disclosure the mechanism for a pair of hinged doors has been illustrated and described. It is obvious however that the same general structure and mode of operation would open and close 35 a single door of conventional design.

Having thus described this invention what is claimed and desired to secure by Letters Patent is:

1. A door operator in the class described, including a door pivotally mounted on a building structure; automatic door closing means interposed between said door and structure; a hydraulic ram on said structure and having an extensible piston rod with a cross head thereon; flexible door opening means connected to said cross-head and door; a pressure inlet conduit to said ram from a source of supply; a discharge conduit from said ram; a magnetic valve in said inlet conduit; a magnetic valve in said discharge conduit; an electric circuit having a remote control switch therein adapted to control the opening and closing of said door and including said magnetic valves; and subcircuits in said electric circuit having means therein controlled by said cross-head and adapted to maintain said door open when said piston rod is extended and to open said magnetic discharge valve when said remote control switch is closed to permit the closing of said door by said closing means.

2. A door operator in the class described, including a door vertically pivoted on a building structure; automatic door closing means interposed between said door and structure; a latch on said door; a hydraulic ram on said structure and having an extensible piston rod with a cross-head thereon; flexible door opening means connected to said latch and cross-head and running through a pulley on said structure; a pressure inlet conduit to said ram from a source of supply and having a magnetic inlet valve therein; and a magnetic valve controlling the discharge from said ram; an electric circuit having a remote control switch therein and including said magnetic valves, whereby said switch controls the opening and closing of said door; and subcircuits

in said electric circuit having means therein controlled by said cross-head and adapted to maintain said door open when piston rod is extended and to open said magnetic discharge valve when said remote control switch is closed, to permit the closing of said door by said closing means.

3. A door operator in the class described, including a pair of doors vertically pivoted in opposed relation on a building structure; latching means engaging said doors; door closing means interposed between said doors and said structure; a ram on said structure and having an extensible piston rod with a cross head thereon; flexible door opening means extending between said cross-head and said latch and running through a pulley on one door and said structure, respectively; and another flexible door opening means extending between said cross-head and the other door; a pressure inlet conduit to said ram from a source of supply and having a magnetic inlet valve therein; and a magnetic outlet valve controlling the discharge from said ram; an electric circuit having a remote control switch therein; and subcircuits in said electric circuit having means therein controlled by said cross-head and adapted to maintain said doors open when said piston rod is extended and to open said magnetic discharge valve when said remote control switch is closed, to permit the closing of said doors by said closing means, and

to close said discharge valve and open said inlet valve when said piston rod is retracted, and said remote control switch is again closed.

4. A door operator in the class described, including a pair of doors vertically pivoted in opposed relation on a building structure having side walls; door closing means attached to said doors by flexible means running through pulleys on said side walls, respectively, to close said doors; fluid pressure means on said structure above said doors and having an extensible member parallel with the plane of said walls; flexible door opening means extending between said extensible member and said doors and running through pulleys on said side walls, respectively; a pressure inlet conduit to said pressure means and having an inlet valve therein; an outlet conduit from said pressure means and having an outlet valve therein; means for closing said outlet valve when said extensible member is retracted and said inlet valve is closed; and remote control means for said valves, whereby said inlet valve may be opened to open said doors when the extensible member is retracted and to open said discharge valve and close said inlet valve when said extensible member is extended, to permit said doors to be closed by said door closing means.
